NECKLACE OR SIMILAR ARTICLE

Florence C. Witmer, New York, N. Y.

Application February 7, 1952, Serial No. 18,421

Term of patent 7 years

(Cl. D45—16)

To all whom it may concern:

Be it known that I, Florence C. Witmer, a citizen of the United States, residing in the city of New York, county of New York, and State of New York, have invented a new, original, and ornamental Design for a Necklace or Similar Article, of which the following is a specification, reference being had to the accompanying drawing, constituting a part hereof.

Fig. 2 is a cross-sectional view taken on the line 2—2 of Fig. 1;

Fig. 3 is a top elevational view of one of the links as viewed on line 3—3 of Fig. 2.

I claim:

The ornamental design for a necklace or similar article, substantially as shown.

FLORENCE C. WITMER.
